EXPLOSIVE ACTUATED STUD DRIVING TOOL
 Robert Temple, Swissvale, and Ernest E. Temple, Mur-
 raysville, Pa., assignors to Mine Safety Appliances
 Company, a corporation of Pennsylvania

Filed Sept. 20, 1960, Ser. No. 57,203
 4 Claims. (Cl. 1—106)

This invention relates to tools with which studs are driven by explosive charges behind them, and more particularly to a tool that cannot be fired accidentally.

It is among the objects of this invention to provide such a tool which is simple to operate, which cannot be fired without being grasped in both hands, and which automatically becomes safe when released from the hands.

In accordance with this invention a barrel is slidably mounted in a sleeve and projects from its front end. The barrel has a cartridge-receiving chamber in its rear end. The sleeve is provided with a longitudinal slot in its side wall as wide and nearly as long as the barrel. The barrel is pivoted in the front end portion of the sleeve to permit the rear end of the barrel to swing out of the sleeve through the slot. A spring normally holds the barrel in its swung-out position, and resilient means hold the barrel in a forward position in the sleeve. Mounted in the sleeve behind the barrel is a breechblock, from the front of which a firing pin can project. A handle is rigidly connected to the sleeve for pushing it forward around the barrel when the barrel is held inside the sleeve and its front end is pressed against a stationary object. The sleeve can be moved forward far enough to move the firing pin against a cartridge in the barrel and to move the breechblock forward around the firing pin. Manually operable means are provided for driving the firing pin forward in the breechblock. Preferably, the tool also is provided with an ejector to aid in pushing the barrel forward in the sleeve as soon as the tool is withdrawn from the work, whereby the barrel will be sure to swing out of the sleeve.

The preferred embodiment of the invention is illustrated in the accompanying drawings, in which

FIG. 1 is a plan view of our tool, with the front end shown in section;

FIG. 2 is a side view partly broken away in section;
 FIG. 3 is a central longitudinal section of the tool ready to fire;

FIGS. 4 and 5 are cross sections taken on the lines IV—IV and V—V, respectively, of FIG. 1; and

FIG. 6 is a cross section taken on the line VI—VI of FIG. 3.

Referring to the drawings, the frame of a tool includes a heavy sleeve 1, the rear end of which is secured to the front end of a trigger housing 2. The rear end of the housing is supported by a handle 3 of any suitable construction. Screwed onto the front end of the sleeve is a collar 4 that holds a rotatable ring 5 on the sleeve. The ring encircles the collar and is screwed into an annular flange 6 on the back of an eccentric shield 7 which is disposed in front of the sleeve. The shield is provided with an opening 8 coaxial with the sleeve. A barrel 9 is slidably mounted in the sleeve and extends forward through the shield and projects in front of it. The rear end of the barrel is located a short distance in front of the rear end of the sleeve. One side of the sleeve, preferably the top side, is provided with a longitudinal slot 10, which is long enough to permit the barrel to normally extend out of the sleeve at an oblique angle as shown in FIG. 2, so that the rear end of the cartridge chamber 11 (FIG. 3) in the barrel is readily accessible to the operator. A portion of the barrel in shield opening 8 is reduced in diameter so that the shield will not

2

interfere with swinging of the rear end of the barrel out of sleeve.

To permit the rear end of the barrel to swing in and out of the sleeve, a pair of diametrically opposite pivot pins 12 are mounted in a barrel a short distance behind the shield. The pins project into longitudinal grooves 13 in the opposite sides of the front portion of the sleeve, so that the pins can both turn and move lengthwise of the sleeve. The barrel is always urged forward in the sleeve by coil springs 14 (FIG. 1) disposed in sockets 15 drilled lengthwise into the sleeve from the inner ends of the grooves. The springs press plungers 16 against the back of the pins. If the grooves 13 extend all the way to the front end of the sleeve, the distance that springs 14 can push the barrel forward is limited by forward extensions 12a of the pins, which also slide in the grooves and engage the back of the shield. When the barrel is in its forward position in the sleeve, the pivot pins are spaced a short distance from the rear ends of the grooves. The barrel normally is held in a swung-out position by means of a leaf spring 17 disposed in a groove 18 (FIG. 3) in the bottom of the sleeve, with its front end held by a rivet 19 while its rear end presses up against the barrel.

The barrel 9 can be swung into the sleeve, where it will be concentric therewith, by grasping the sleeve and barrel in one hand and squeezing them together. When the barrel is in its inner or operative position, it is directly in front of a breechblock 20 that engages the front end of the trigger housing 2. A firing pin 21 (FIG. 3) is slidably mounted in the breechblock and projects from its front end when the tool is not ready for firing, but the projecting pin normally is spaced from the barrel even when the barrel is entirely within sleeve 1. The pin is held in its forward position by a hammer 22 engaging its rear end, the hammer being slidably mounted in housing 2 and urged forward by a coil spring 23.

The hammer can be retracted and released by any suitable manually operated means. For example, a trigger 25, projecting from the housing, may be provided inside the housing with a slot 26 extending lengthwise of the tool and receiving cross pins 27 and 28 anchored in the housing. The front end of the slot curves upward and the central portion is provided with an upwardly extending notch 29. The notch and front end of the slot are same distance apart as the two cross pins. The trigger normally is held in a forward position because its rear end projects into a vertical slot 31 in the front end of a plunger 32 slidably mounted in a bore 33 in the tool handle. The plunger is urged forward by a coil spring 34 behind it. The trigger carries a pivoted sear 36 that normally engages the bottom of the hammer in front of a radial shoulder 37. The sear is urged upward by a small spring 38 attached to the trigger. When the trigger is pulled backward toward the hammer, the sear engages the hammer shoulder and retracts the hammer until the trigger moves downward on cross pins 27 and 28 so that the hammer shoulder can move forward over the sear. When the trigger is released, it will be pushed forward by plunger 32, and the sear will ride forward across the shoulder and snap into operative position once again.

To operate this tool, a cartridge 40, supporting the rear end of a stud 41, is inserted in cartridge chamber 11 while the barrel is in its outer or safety position shown in FIG. 2. The barrel is then pressed down into the sleeve and held there while the muzzle is placed against the object 42 (FIG. 3), into which the stud is to be driven. The tool handle then is pushed ahead to slide the sleeve 1 forward on the barrel until the breechblock engages the cartridge, as shown in FIG. 3. By that time the rear wall of slot 10 will have moved a short distance over the rear end of the barrel, which therefore will become locked in the sleeve. During forward move-

ment of the sleeve the firing pin engages the primer of the cartridge and stops before the breechblock engages the cartridge, whereby the hammer spring 23 is compressed slightly. The tool now is ready to be fired, which is done by pulling back the trigger as previously explained in order first to retract the hammer and then to release it. When the hammer is driven forward by its spring against the firing pin, the latter is moved forward in the breechblock and detonates the cartridge to drive the stud out of the barrel and through the muzzle block and into work 42. The moment forward pressure on the tool handle is released by the operator, the barrel and muzzle block are supposed to move forward in the sleeve so that the rear end of the barrel will clear the rear end of slot 10. Thereupon, leaf spring 17 will swing the barrel up out of the sleeve to the position shown in FIG. 2.

If springs 14 can be made strong enough, they will push the barrel forward in the sleeve, but since those springs must necessarily be quite small it is preferred to guarantee that the barrel will be ejected from the sleeve by placing a much stronger coil spring 45 behind the barrel. This spring encircles the breech-block inside of a cup-like ejector 46 slidably mounted in the sleeve. The ejector is urged forward by spring 45, but its forward movement is limited by a pin 47 extending through the side wall of the sleeve and into a longitudinal groove 48 in the outside of the ejector. The front position of the ejector, as shown in FIG. 2, is such as to substantially engage the rear end of the barrel when it is swung down into the sleeve, but not such as to prevent the barrel from being swung down. The front wall of the ejector has a central opening 49 through it in line with the firing pin and the cartridge chamber. The breechblock has a reduced front end portion small enough to extend through the ejector opening and engage the cartridge when the sleeve is pushed forward around the ejector and barrel in preparing the tool for firing.

The spent cartridge can be removed from the barrel while the rear end of the barrel is projecting from the sleeve. This operation is facilitated by the use of a cartridge ejector, which includes a sleeve 51 encircling the rear end portion of the barrel in an annular recess and having an inwardly extending rear end flange 52 that engages the front surface of the upper half of the cartridge flange. Secured to the top of sleeve 51 is a knob 53 that is held in place by a stud 54, which projects into a longitudinal slot 55 in the top of the barrel to prevent sleeve 51 from rotating on the barrel. The slide is moved backward by its knob 53 to cause flange 52 to push the cartridge part way out of the cartridge chamber so that it can be grasped by the fingers and removed the rest of the way.

It will be seen that this tool cannot be fired until the barrel has been swung completely into the sleeve, an operation that requires the use of one hand while the other hand is holding the tool handle. The moment the tool is laid down or accidentally dropped, the barrel swings out of the sleeve and therefore away from the firing pin so that the cartridge cannot be detonated. Therefore, the tool is rendered safe automatically.

We claim:

1. A stud driving tool comprising a sleeve, a barrel

slidably mounted in the sleeve and projecting from its front end, the barrel having a cartridge-receiving chamber in its rear end, the sleeve having a longitudinal slot in its side wall as wide as the barrel, means pivoting the barrel in the front end portion of the sleeve in a position to permit the rear end of the barrel to swing out of the sleeve through said slot, a spring normally holding the barrel in its swung-out position, resilient means normally holding the barrel in a forward position in the sleeve, a breechblock mounted in the sleeve behind the barrel, a firing pin projectable from the front of the breechblock, a handle rigidly connected to the sleeve for pushing it forward around the barrel when the barrel is inside the sleeve and its front end is pressed against a stationary object, the sleeve being movable forward far enough to move the firing pin against a cartridge in said chamber and to move the breechblock forward around the firing pin, and manually operable means for driving the firing pin forward in the breechblock.

2. A tool according to claim 1, in which said spring is a leaf spring disposed between the barrel and the inner wall of the sleeve at the side opposite to said slot.

3. A stud driving tool comprising a sleeve, a barrel slidably mounted in the sleeve and projecting from its front end, the barrel having a cartridge-receiving chamber in its rear end, the sleeve having a longitudinal slot in its side wall as wide as the barrel, means pivoting the barrel in the front end portion of the sleeve in a position to permit the rear end of the barrel to swing out of the sleeve through said slot, a spring normally holding the barrel in its swung-out position, resilient means normally holding the barrel in a forward position in the sleeve, a barrel ejector slidably mounted in the rear end of the sleeve and provided with an opening coaxial with the muzzle block, a spring behind the ejector normally holding it in a position where its front surface will engage the rear end of the barrel when the latter is inside the sleeve, a breechblock mounted in the rear end of the sleeve behind the front of the ejector, a firing pin projectable from the front of the breechblock, a handle rigidly connected to the sleeve for pushing it forward around the barrel when the barrel is held inside the sleeve and its front end is pressed against a stationary object, the sleeve being movable forward far enough to press the firing pin against a cartridge in said chamber and to move the breechblock forward around the firing pin and through said ejector opening, and manually operable means for driving the firing pin forward in the breechblock.

4. A tool according to claim 3, in which said ejector is cup-shape and encircles the breechblock.
